(57) **ABSTRACT**

The present invention is directed to systems and methods that permit dropper bottles to be filled without removing the dropper spout from the body of the bottle. As such, dropper bottles having integrated spouts can be filled after manufacture of the bottle, which facilitates the aseptic preparation of compounded solutions. In some embodiments, the inventive bottle includes a fill valve on the base and is vented through the nozzle. In other embodiments, the bottle is both filled and vented via the nozzle.

SYSTEMS AND METHODS FOR FILLING AND VENTING DROPPER BOTTLES

CLAIM OF PRIORITY

The present application claims priority under 35 U.S.C. Section 119 to U.S. Provisional application having Ser. No. 63/333,969, which was filed on Apr. 22, 2022, as well as U.S. Provisional application having Ser. No. 63/333,985, which was filed on Apr. 22, 2022, both of which are incorporated by reference herein in their entireties.

BACKGROUND OF THE INVENTION

Field of the Invention

The present invention pertains to dropper bottles having integrated filling and venting structure, allowing the dropper bottles to be filled without removing the nozzle from the bottle.

Description of the Related Art

Sterile ophthalmic compounding is currently widely used in 503B, 503A, eye institutes, and hospital pharmacy facilities worldwide. In addition to human drug compounding, eyedropper products can also apply to veterinary compounding. A typical ophthalmic drug dropper, when compounded, consists of a bottle, cap and spout which must be filled and assembled while maintaining aseptic technique. Aseptic technique requires strict procedures for preparing the drug in a sterile, Class 5 clean room environment under a laminar flow hood and avoiding touching component surfaces which can contact the drug. Since the bottle, spout and cap are separate components it makes the aseptic preparation extremely difficult. The most critical part is the spout which is in direct contact with the drug and this component typically must be put on the bottle after it has been filled without touching it.

Therefore, there is a need in the art to supply sterile, enclosed (in the case of a dropper bottle having a unitary dropper spout and body) or pre-assembled dropper bottles which can be filled by compounders without having to remove the spout from the body, thereby maintaining the sterile environment inside of the bottle.

This present invention eliminates the handling of multiple components by allowing the spout to be integrated into the bottle and/or preassembled and delivered to the compounder with a sterile interior.

SUMMARY OF THE INVENTION

Various embodiments of the present invention are disclosed herein, one aim of which is to provide a dropper bottle that can be filled without removing the nozzle from the body, thereby maintaining aseptic technique and a sterile bottle interior. In one embodiment, the invention permits the dropper bottle to be filled via the dropper spout by providing suitable vent structure in the bottle and/or nozzle. In an alternative embodiment, the bottle may be filled via a separate fill valve, which is preferably located on the base of the bottle.

In one embodiment, the invention includes a nozzle having a plurality of fluid pathways. In such an embodiment, the dropper spout of the nozzle may be at least partially segregated into a plurality of fluid pathways, including at least liquid pathway and an air vent. The liquid pathway

in communication with the dropper spout, allowing fluid communication between the interior of the bottle and the exterior of the bottle, such as for filling the bottle and for administering the contents. The vent includes a vent tube in fluid communication with an air outlet. The vent tube runs at least partially into the body of the bottle to help preclude liquid from pouring out of the air vent when the bottle is inverted. The air outlet can be disposed on the surface of the nozzle. In a preferred embodiment, the air outlet is separated from the dropper spout by a predetermined distance to avoid inadvertently filling the bottle through the vent. Otherwise, the air outlet can be at least partially shielded such that care need not be taken when filling the bottle, as liquid will be automatically diverted into the liquid pathway via the shield.

15 The air outlet may also comprise a one-way valve.

In another embodiment, the invention includes a fill valve at the base of the bottle such that the bottle can be filled from the bottom. This allows the nozzle to operate as an air vent while the bottle is being filled. Alternatively, a dedicated 20 vent (as discussed above) may also be included if desired. In such an embodiment, the fill valve may comprise any of a variety of one way valves such as a duck bill valve, a septum valve, a check valve, a ball valve, and the like. The exterior portion of the valve can also comprise any of a variety of standard fittings, such as a luer fitting, which facilitates filling the bottle via a syringe. Alternatively, a needless connector may be used to fill the bottle from a repeater pump.

One alternative embodiment for a one-way valve includes 30 a plug having a tab on one end and a sealing end on the other end of the plug. The sealing end is disposed inside of the bottle with the tab protruding from the exterior of the bottle via an aperture in the base of the bottle. Prior to filling, the plug is disposed in a substantially free floating orientation, 35 which allows the bottle to be filled. Once filled, the tab can be pulled, and the plug seated in a substantially sealed orientation. The diameter of the sealing end should be larger than the aperture in the bottle, and may include a gasket or some other material to facilitate a substantially water tight seal.

The invention may also include a cap for the bottle which is designed to be partially installed prior to filling in order to allow air to escape during filling. Once the bottle is filled, the cap can be secured in a substantially water or air tight 45 orientation, such as by a quarter turn of the cap. If desired, the cap may include any of a number of tamper evident features, such as breakaway tabs.

In all embodiments, any of a variety of filters and filter media may be incorporated into the bottle. By way of 50 example, it may be desirable to include a filter membrane between the dropper spout and the body of the bottle. In certain embodiments, a filter having a filter distance of 0.4 microns may be desired. If a repeater pump is used to fill the bottle, it may be desirable to use a hydrophobic filter on the order of 12 microns in the pump itself.

The present invention is also directed to a method of filling a sealed dropper bottle, whether the bottle is unitary or preassembled. The method according to one embodiment can include providing an empty and sterile dropper bottle; 60 providing a solution to be transferred to the dropper bottle; without removing the nozzle from the body of the bottle, filling the dropper bottle with the solution via a fill valve located on the bottom of the bottle; and sealing the dropper bottle by securing a cap to the dropper bottle. The method according to another embodiment can include providing an empty and sterile dropper bottle; providing a solution to be 65 transferred to the dropper bottle; without removing the

nozzle from the body of the bottle, filling the dropper bottle with the solution via a liquid pathway located on the nozzle of the bottle; and sealing the dropper bottle by securing a cap to the dropper bottle.

These and other objects, features and advantages of the present invention will become clearer when the drawings as well as the detailed description are taken into consideration.

BRIEF DESCRIPTION OF THE DRAWINGS

For a fuller understanding of the nature of the present invention, reference should be had to the following detailed description taken in connection with the accompanying drawings in which:

FIG. 1 is a cross section of a bottle according to one embodiment of the present invention.

FIG. 2 is a cross section of a top end of a bottle according to one embodiment of the present invention.

FIG. 3 is a cross section of a bottle according to another embodiment of the present invention.

FIG. 4 is a cross section of a base of a bottle according to another embodiment of the present invention.

FIG. 5 is a cross section of a base of a bottle according to yet another embodiment of the present invention.

Like reference numerals refer to like parts throughout the several views of the drawings.

DETAILED DESCRIPTION OF THE PREFERRED EMBODIMENT

FIG. 1 is a cross section of a bottle 1 according to one embodiment of the present invention. As discussed, the invention is designed to permit the filling of bottles having an integrated nozzle 100 and body 210. Therefore, the drawings depict a unitary design. However, it should be appreciated that the present invention is not limited merely to unitary bottles, and that the features of the present invention may also be employed with more traditional dropper bottle configurations wherein the nozzle 100 and body 210 are separate, but are delivered to a compounder in a pre-assembled configuration to preserve sterility inside the bottle.

The bottle 1 of FIG. 1 is designed to be filled through the nozzle 100. In particular, the bottle 1 includes a top end 10 having a nozzle 100. The nozzle includes both a liquid pathway 110 and vent 120. The vent 120 is segregated from the liquid pathway 110 and is instead disposed in communication with a vent tube 121 that runs at least partially into the body 210 of the bottom end 20. In this regard, any of a variety of filling apparatus can be applied to the nozzle 100 without regard to the specific orientation of the liquid pathway 110 compared to the vent 120, because any liquid will be automatically diverted into the liquid pathway 110. FIG. 2 is a detail view of one embodiment in which the air outlet 125 of the vent is disposed on the side of the nozzle 100 wherein the shield 130 can be seen extending in at least partially covering orientation over the air outlet 125.

FIG. 3 is a cutaway view of a bottle 1 according to yet another embodiment of the present invention in which the bottle 1 may be filled from the base 220. In such an embodiment, the base 220 may include a fill valve 225 which may comprise any of a variety of configurations. In a preferred embodiment, the fill valve 225 may comprise a one-way valve. As a non-limiting example, FIG. 4 depicts a duck bill valve 225' in which two opposing elastomeric surfaces meet at an oblique angle. When fluid is directed through the duck bill valve 225' from the exterior of the

bottle, the surfaces are forced apart and liquid is permitted to flow through the valve. When fluid is forced from the interior of the bottle, however, the surfaces are forced together, and no fluid is permitted through.

As another non-limiting example, FIG. 5 shows a fill valve 225" having a configuration of a plug 300 which may be used to manually seal an aperture in the bottom end of the bottle after filling. In particular, the plug 300 includes a sealing end 320 inside the bottle and a tab 310 protruding exteriorly of the bottle. When in a free-floating orientation, the sealing end is not disposed directly against the aperture in the bottom of the bottle, and the plug 300 will permit fluid to flow into the bottle. However, a user may grasp the tab 310 and pull the plug 300 into a sealing configuration, in which the aperture is sealed. The plug 300 may include a gasket or pressure activated adhesive on the sealing end 320 to ensure a substantially water tight seal.

FIG. 3 also depicts a cap 30 installed on the bottle 1. In a preferred embodiment, the bottle 1 is provided to a compounder with the cap 30 in a partially installed orientation. This ensures that the cap 30 is not air-tight prior to filling such that the bottle 1 can be vented during filling. However, the partial installation of the cap 30 also helps ensure that the interior of the bottle 1 maintains a sterile environment. Once the bottle 1 is filled, the compounder can complete the installation of the cap 30, such as by making a quarter turn of the cap 30.

It will be recognized that a variety of fittings and connections may be employed depending upon the particular use case envisioned. In certain cases, pharmaceutical compounding is conducted in very small batches. In this case, the user may conveniently fill one or a small number of bottles from a syringe. As such, a luer fitting on the fill valve 225 may be appropriate. Otherwise, for somewhat larger batches, it is known that the various repeater pumps used by compounders may have other fittings, and the fill valve 225 can be configured to fit any of a number of widely available pumps.

Since many modifications, variations and changes in detail can be made to the described embodiments of the invention, it is intended that all matters in the foregoing description and shown in the accompanying drawings be interpreted as illustrative and not in a limiting sense. Thus, the scope of the invention should be determined by the appended claims and their legal equivalents.

What is claimed is:

1. A dropper bottle comprising:
a top end and a bottom end;
a nozzle at said top end;
a fill valve located at said bottom end, said fill valve comprising a plug disposed interiorly of the dropper bottle, said plug including a tab extending exteriorly of the dropper bottle,
said plug disposed in a free-floating orientation concurrent to fluid flow into the dropper bottle, and
said plug manually pulled from said free-floating disposition, via said tab, into a sealing configuration with said bottom end, subsequent to said fluid flow.
2. A dropper bottle comprising;
a top end and a bottom end
a nozzle connected to said top end and including a plurality of fluid pathways;
at least a first of said plurality of fluid pathways comprising a liquid path for at least dispensing medication from said dropper bottle;

- 5
at least a second of said plurality of fluid pathways comprising a vent, said vent including an air outlet disposed on said nozzle for air escape when filling said dropper bottle,
a shield connected to said nozzle and extending outwardly 5 therefrom in at least partially covering relation to said air outlet,
a fill valve located at said bottom end and comprising a plug disposed interiorly of the dropper bottle, said plug including a tab extending exteriorly of the dropper 10 bottle,
said plug disposed in a free-floating orientation concurrent to fluid flow into the dropper bottle, and
said plug manually pulled from said free-floating disposition, via said tab, into a sealing configuration with 15 said bottom end, subsequent to said fluid flow.
3. The dropper bottle as recited in claim 2 wherein said first pathway is segregated from said second pathway.
4. The dropper bottle as recited in claim 2 wherein said vent is disposed in communication with a vent tube. 20
5. The dropper bottle as recited in claim 4 wherein said vent tube extends at least partially into said bottom end.
